UNITED STATES PATENT OFFICE

2,516,341

GRAVITY FED DART MAGAZINE

Henry Raffeis, Huntington Park, Calif.

Application April 19, 1946, Serial No. 663,578

2 Claims. (Cl. 124—49)

1

The present invention relates to improvements in projectile propelling devices and deals more particularly with a magazine crossbow capable of rapidly projecting a series of darts or similar projectiles toward a target.

A general object of this invention is to provide a weapon generally similar in appearance and mode of operation to a conventional firearm, and to provide the weapon with a plurality of darts so arranged in a magazine in the weapon that the string of a bow mounted thereon can be rapidly engaged with the darts, successively, for successive propulsion of said darts from the weapon.

Another object of the invention is to provide a weapon of the type referred to which embodies novel means for arranging and aligning a plurality of darts whereby the string of a bow can readily engage said darts for successive propulsion thereof from the weapon.

Another object of the invention is to provide a weapon for firing a plurality of darts successively, in which the next dart to be fired is positively held by a trigger or releasing means and in which means are provided for hooking the string of a bow to said dart whereby, upon actuation of the releasing means, the stored energy of the bow becomes effective to propel said dart from the weapon.

A further object of the invention is to provide a dart propelling weapon provided with a storage compartment, preferably in the stock of the weapon, in which compartment a quantity of darts may be stored together with certain adjuncts of the weapon, such as extra bow strings, wax for the strings, etc.

My invention also has for its objects to provide such means that are positive in operation, convenient in use, easily installed in a working position and easily disconnected therefrom, economical of manufacture, relatively simple, and of general superiority and serviceability.

The invention also comprises novel détails of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a top plan view, partly broken, of a weapon embodying the present invention.

Fig. 2 is a side elevational view thereof, the front part of the weapon being broken away.

Fig. 3 is an enlarged end view of the stock of the weapon and shown partly open to expose a storage compartment provided in the stock.

Fig. 4 is a vertical sectional view, as taken 5 through the center of Fig. 3.

Fig. 5 is a broken plan view of the weapon in greater detail.

Fig. 6 is a longitudinal elevational view thereof, partly in section.

10 Figs. 7, 8 and 9 are cross-sectional views, as taken on the lines 7—7, 8—8 and 9—9 respectively, of Fig. 6.

Fig. 10 is an end view of the discharge end of the weapon.

15 Fig. 11. is a broken side elevational view of a block for drawing the bow string into dart engagement.

Fig. 12 is an enlarged sectional view of the head end of one of the darts.

20 head end of one of the darts.

20 The dart-propelling weapon which is shown in the drawings comprises, generally, a stock 15, a magazine 16 for a plurality of darts 17, a barrel 18 through which the darts pass as they are being
25 propelled from the magazine, a generally conventional bow 19 mounted at an intermediate portion of the barrel, a manually slidable block 20 for effecting hooking engagement of the string of said bow with the darts 17 in the magazine, successively, trigger means 21 normally having
30 detent engagement with the darts and adapted to effect release of the same for propulsion from

the weapon by the bow, and means 22 in the magazine for effecting rotational alignment of the darts whereby the trigger means may effectively engage the darts and the bow string may readily hook onto said darts.

The stock 15 and the housing 23 of the weapon, as shown, may be made integral. The stock is generally conventional in form and is made of wood or other suitable material. A storage compartment 24 is formed by a metallic extension

25 and a plurality of holes or seats 26 formed in the end of the stock wherein the darts 17 may be stored when the weapon is not in use. A cover 27 is provided for the compartment, said

cover, when closed, comprising the end of the stock and when swung open on its pivot 28, giving access to the compartment. A latch 29 is provided for normally holding the cover closed.

provided for normally holding the cover closed. By providing a partition 30 extending from the end face 31 of the stock to the cover 27, when closed, an auxiliary compartment 32 is provided for housing extra bow strings, string wax, etc.

end or nose 35. Said nose is preferably somewhat pointed and formed as a metallic shell fitted to the shaft and held thereon as by punched tins 36. The nose is provided with an opening 37 for engagement with the trigger means 21. At an intermediate portion of the shaft 33 and on the opposite side of the dart from the opening 37, there is provided a hooking notch 38 shaped to retain the string of the bow 19. Between the notch 38 and the feathered end 34, and formed in the sides of the dart (with the hole 37 facing down and the notch 38 facing up), a pair of opposed flats 39 are provided, said flats being preferably outwardly sloped whereby they are triangular in shape with their apices directed rearwardly.

The magazine 16 is formed in the housing 23 and comprises a chamber 40 extending downwardly from the top of the housing. Said chamber 40 has a bottom wall 41 upon which the darts 17, rest, end walls 42 and 43 spaced somewhat greater than the length of a dart, and side walls 44 spaced slightly more than the diameter of a dart.

It will be evident that a plurality of darts may be placed in the magazine chamber 40 and that said darts will be arranged longitudinally one above the other. Means are provided for tightly, yet releasably holding the darts. As shown, said means comprises a flat spring 45 hinged at 46 to permit access to the chamber 40 and adapted to be positioned in overstanding relation to the darts to press upon them when a hinged cover 47 is closed over the spring 45 and latched in place by a swing dog 48.

As before pointed out, it is desired that the openings 37 and the notches 38 of the darts be so positioned that the trigger means 21 and the string of bow 19, respectively, will surely engage them. Accordingly, the side walls 44 of the magazine chamber are laterally recessed for a pair of flat spring members 49 extending from top to bottom of said chamber and designed to engage the mentioned flats 39 of the darts. By placing the darts into the magazine in the manner indicated, the spring members 49 will obviate their inadvertent rotation during downward movement of the darts and assure proper relational positioning of the openings 37 and notches 38.

The barrel 18 comprises a forwardly extending member of wood or other suitable material, secured between the outer walls 50 of the magazine. Said barrel is formed with a longitudinal slot 51 so that said barrel, in effect, is bifurcated to form upper and lower portions 52 and 53, respectively. The lower barrel portion 53 is provided with a groove 54 co-extensive with the slot 51. The slot 51 terminates at an intermediate portion of the barrel and a passage 55 extends from said end of the slot through the end 56 of the weapon. The slot 51 and groove 54, and the passage 55 are of sufficient size to permit ready passage of a dart therethrough.

At the mentioned end of the slot 51 there is provided a pair of side blocks 57, thereby thickening the barrel at that point. The bow 19 is mounted in a seat 58 formed transversely in the top of said thickened portion of the barrel. The flexible wooden member 59 of the bow is fitted into said seat at such an angle as to bring the bow string 60, when pulled, into hooking engagement with the notch 38 of the lowermost dart 17. A swing dog 61 is used for holding the bow seated in position.

The block 20 is arranged to slide on the mentioned lower portion 53 of the barrel 18 along a path from the blocks 57 to an intermediate portion of the magazine. Said block is formed with a longitudinal groove 62 loosely engaging said barrel portion 53, is provided with a hand-grasping portion 63 for effecting movement of the block toward the magazine, and is formed with side finger-gripping recesses 64 for effecting movement of said block away from the magazine. The upper portion of the block is provided with a pair of plates 65 directed toward each other and operating in the slot 51. A notch 66 is provided in the block for engaging the bow string 60 by beveling the adjacent portions of the plates 65 and the block end directed toward the magazine.

The trigger means 21 comprises a metal bar 67 pivoted at an intermediate point at 68 to the bottom wall 41 of the magazine. Said bottom wall is longitudinally slotted at 69 for the forward end 70 of said bar, the end of which is provided with a detent 71 for engagement with the hole 37 of the lowermost dart 17. The rear end of the bar 67 is provided with a downwardly curved end 72 comprising a finger trigger. A spring 73, set into the stock, is arranged to press the bar 67 so that the detent 71 is urged into the hole of the dart. A trigger guard 74 is provided for the finger trigger 72.

The weapon is further preferably provided with a rear sight 75 rearward of the magazine 16 and a front sight 76 at the front end of the barrel.

After the magazine has been filled with darts as illustrated, the bow string 60 is engaged with the notch 66 of the block and with the stock of the weapon against the shoulder, said block is pulled rearwardly to cause flexing of the bow 19. The block is moved along the barrel part 53 until the plates 65 pass on either side of and between the two lowermost darts as seen in Figs. 6 and 8. Continued movement of the block 20 will bring the bow string into exact alignment with the notch 38 of the lower of said darts and said string becomes hooked in said notch upon return movement of block 20 to its initial position. By pressing the finger trigger 72, the detent 71 is withdrawn from the hole 37 of said dart and the stored energy in the bow becomes effective to propel said dart along groove 54 and out of the weapon through passage 55. It will be obvious that the darts in the magazine 16 can be discharged as rapidly as the block 20 can be "pumped" back and forth and that the weapon can be handled in exactly the same manner as a repeating or pump gun is handled.

It is believed clear without further illustration that resilient cushion means may be interposed between the wooden member 59 and the seat 58.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In combination, a magazine, opposed resilient elements within the magazine, and a stack of darts in the magazine between said resilient elements, each dart, on opposite sides of the body thereof, having a flat face terminating in an end

shoulder, said flat faces of the darts being in lateral engagement with said resilient elements to thereby hold said darts against rotation in the magazine, the darts, successively, being adapted to be withdrawn from the magazine and from between the resilient elements in a direction moving the mentioned shoulders away from the resilient elements.

2. In combination, a stack of darts, each dart on the opposite sides of the body thereof, having a flat face terminating in an end shoulder; and opposed resilient members on each side of the stack and having lateral engagement with the flat faces of the darts to hold the same non-rotationally, the darts, successively, being adapted to be withdrawn from between the resilient elements in a direction moving the mentioned shoulders away from the resilient elements.

HENRY RAFFEIS.
